UNITED STATES PATENT OFFICE.

ELIZABETH BOGGIS, OF PHILADELPHIA, PENNSYLVANIA.

STAMP AND ENVELOP MOISTENER.

SPECIFICATION forming part of Letters Patent No. 608,642, dated August 9, 1898.

Application filed May 5, 1897. Serial No. 635,199. (No model.)

To all whom it may concern:

Be it known that I, ELIZABETH BOGGIS, of Philadelphia, in the county of Philadelphia and State of Pennsylvania, have invented 5 certain new and useful Improvements in Stamp and Envelop Moisteners; and I do hereby declare the following to be a full, clear, and exact description of the invention, such as will enable others skilled in the art to which 10 it appertains to make and use the same.

My invention relates to improvements in envelop and stamp moisteners, the object of the same being to provide a simplified construction of device embodying certain advantages hereinafter more fully described, and specifically set forth in the appended claims.

In the accompanying drawings, illustrating the invention, Figure 1 is a vertical sectional view of the device. Fig. 2 is a perspective 15 view of the cover removed, and Fig. 3 is an enlarged detail view of the chamois attachment.

Similar numerals of reference designate corresponding parts throughout the several 20 views.

Referring to the drawings, the numeral 1 designates a case or receptacle of any suitable form and provided with exterior ornamentation, if desired. In the present instance 25 the case is constructed of barrel or cylinder shape and is provided with interior screw-threads 2 throughout its length and with exterior screw-threads 3, adjoining the top thereof, adapted to receive a bell-shaped cover 4, which is provided with a pen-wiper 5, of cloth 30 or other suitable material. The said case is also provided with a spout 6, closed by a stopper 7.

A sponge 8 or other suitable absorbent material is placed within the case or receptacle and is adapted to absorb the water or fluid contained therein.

9 designates a covering or shielding of chamois, which is attached to a threaded ring 10, which is adapted to engage with the threads on the interior of the case. In practice the sponge is placed in the chamois in a dry condition and secured therein by inwardly-projecting spring-pressed clamps 11 on the interior of the threaded ring and expands to completely fill the chamois on contact with the fluid contained within the case. The provision of the screw-threaded ring enables the chamois and sponge to be adjusted in the case

to keep the absorbent material always in contact with the fluid or moistening material and to compensate for the loss of the latter. It will be understood that in use the stamp or flap of the envelop is pressed down upon the chamois covering, through which will exude 60 the fluid or moistening material.

The case or receptacle is designed to be filled with the fluid or moistening material. Preferably I employ a mixture of chlorid of sodium, cologne, or some suitable perfume 65 and water incorporated in suitable proportions. The purpose of the chlorid of sodium is to secure uniform dampness of the chamois at all times and the perfume to impart a pleasant odor to the moistening fluid. It will 70 be observed that the spout 6 at the side of the cup subserves the purpose of providing a convenient means for replenishing the water-supply in the cup without separating any of the parts and is at the same time adapted 75 to be tightly closed to prevent evaporation at this point. This a feature which I believe to be new, and its importance will be readily perceived.

Having thus described my invention, what 80 I claim as new, and desire to secure by Letters Patent, is—

1. In stamp and envelop moisteners, the combination of an interiorly-threaded case or receptacle, an exteriorly-threaded clamping-ring movable up and down therein, a sheathing or cover of chamois or fabric attached to the said clamping-ring, and absorbent material filling said covering or sheathing, substantially as described. 90

2. An envelop and stamp moistener, comprising an interiorly-threaded case or receptacle, a clamping-ring adjustable up and down therein and provided on the interior thereof with spring-pressed clamps, a sheathing or covering of chamois or fabric attached to the said ring, and absorbent material filling said sheathing or covering and retained in position by the said spring-pressed clamps, substantially as described. 95

In testimony whereof I have signed this specification in the presence of two subscribing witnesses.

ELIZABETH BOGGIS.
